COMBINED TOOTHBRUSH AND TOOTHBRUSH HANDLE

Julian Robert Aymar, 2018 E. 67th St., Brooklyn, N.Y.

Filed Apr. 23, 1963, Ser. No. 74,589

Term of patent 3½ years

(Cl. D9—2)

Fig.1

Fig.2

Fig.3

Fig.4

FIGURE 1 is a front view of the combined toothbrush and toothbrush handle showing my new design.

FIGURE 2 is a side view.

FIGURE 3 is a top view.

FIGURE 4 is a bottom view.

The rear of the toothbrush not shown is like the front shown, except as otherwise indicated in FIGURES 2 and 3.

I claim:

The ornamental design for a combined toothbrush and toothbrush handle, as shown and described.
